(57) **CLAIM**

The ornamental design for a display screen or portion thereof with graphical user interface, as shown and described.

DESCRIPTION

The FIGURE is a front view of a display screen or portion thereof with graphical user interface showing our new design.

The dot-dash broken lines illustrate a display screen or portion thereof. The pair of curved broken lines passing through the display screen or portion thereof illustrate a symbolic break in the article. The remaining broken lines illustrate portions of the the graphical user interface. None of the broken lines form part of the claimed design. The appearance of any portion of the article between the curved break lines forms no part of the claimed design.

The pair of curved broken lines illustrate symbolic breaks and form no part of the claimed design. The appearance of any portion of the article between the curved break lines forms no part of the claimed design.
